Ernest Hopkins

UNITED STATES PATENT OFFICE.

WILLIAM J. KENT, OF NEW YORK, N. Y., ASSIGNOR TO THE MECHANICAL RUBBER COMPANY, A CORPORATION OF NEW JERSEY.

MACHINE FOR TRIMMING FLASHED EDGES ON BINDING.

1,382,651.

Specification of Letters Patent. Patented June 28, 1921.

Application filed March 3, 1920. Serial No. 362,958.

To all whom it may concern:

Be it known that I, WILLIAM J. KENT, a citizen of the United States, residing in the borough of Brooklyn, city of New York, county of Kings, and State of New York, have invented certain new and useful Improvements in Machines for Trimming Flashed Edges on Binding, of which the following is a full, clear, and exact description.

10 This invention relates to a machine for trimming flashed edges on binding, more particularly to a machine for trimming the edges of a forked binding of rubber or similar material such as is used on the margins 15 of matting runners.

This binding is formed with a tapering edge at one side and at the other side is split or forked, the margin of the runner being inserted in the fork and the portions forming the fork being then sewed or otherwise secured to the runner. In the manufacture 20 of this binding a flash is formed on the closed edge and also at the edges of each of the portions forming the fork. Previous to my invention it has been necessary to trim the 25 flash portions by hand, which is a relatively slow and expensive method, and requires considerable skill on the part of the operator to uniformly trim the product.

30 An object of my invention is to provide a simple and efficient machine for trimming the flashed edges of binding.

Another object of my invention is to provide means for trimming the flashed edges of 35 a forked binding having a closed and an open side.

A further object of my invention is to provide means for accurately guiding to a trimming device either side of a binding having 40 differently formed side edges.

A further object is to provide a machine which is readily adjustable to handle different sizes of binding.

45 A still further object of my invention is to provide a machine for trimming the flash from both forked side edges of a binding at equal distances from the closed edge.

For a full disclosure of the invention reference is had to the accompanying specification and drawing in which latter—

50 Figure 1 is a top plan view of a machine embodying my invention.

Fig. 2 is a side elevation with parts in section.

Fig. 3 is an enlarged detail showing the 55 manner of trimming the closed edge of the binding.

Fig. 4 is a detail of the cutter mechanism.

Referring to the drawings the numeral 1 represents the base of the machine from 60 which rise the uprights 2, 3 and 4. A shaft 5 carrying a drive pulley 6 is mounted in bearings 7 and 8 secured to the respective uprights 3 and 4 and carries at its free end a rotary cutter 9. A second shaft 10 carrying a drive pulley 11 is disposed above the first shaft and is mounted in bearings 12 and 13, which bearings are adjustably secured to the respective uprights 3 and 4 by means of screws 14 passing through slots 15 in the uprights and threaded into the bearings. The free end of the shaft 10 carries a rotary cutter 16 coacting with the cutter 9, while the opposite end of the shaft passes through a slot 17 in the upright 2 to allow the shaft to 75 be adjusted as previously described.

At the front of the machine is a work bed 18 supported on legs 19. A circular guide 20 having a peripheral guide groove 21 is 80 adjustably mounted on the work bed 18 by means of a threaded eccentric stud 22 and nut 23. Adjacent the rotary cutters is a transverse guide 24 having a concave upper surface adapted to coact with the binding in a manner to be hereinafter described, the 85 guide being held in place by dowels 25. In rear of the cutters the work bed is provided with an upwardly extending ledge 26 formed with bores 26' in which the opposite ends of a guide 27 may be secured by means of the 90 thumb screws 28. Projecting upwardly from the work bed are posts 29 formed with bores 30 in which the ends of the guide 27 may also be secured when desired by the thumb screws 31. The upper cutter 16 is protected by a 95 guard 32, and attached to one end of this guard is a spring presser foot 33 adapted to coact with the guide 24 to hold the binding in position in a manner to be later described.

In operation the guide 27 is arranged as 100 shown in Figs. 1 and 2 with its ends secured in the ledge 26. The binding 34 is then disposed with the outer margin of its closed side 105 engaging the guide groove 21 and the guide 27 is disposed within the fork in engagement with the inner surface of its closed side. The lower one of the forked portions 36 rests upon the concave upper surface of

the guide 24 and the upper forked portion is held against the lower one by the presser foot 33. The necessary adjustments of the guides 20 and 27 are, of course, made to grip 5 the closed side of the binding between them without unnecessary pressure and to at the same time dispose the forked edges in proper relation to the cutters 9 and 16 for trimming. It will be noted that by use of the concave 10 guide 24 the lower forked portion is raised to approximately the center line of the closed side 35 and the flashed edges of both the forked portions 36 are trimmed at substantially the same distance from the closed side 15 35, whereas if the cutters were disposed to cut the forked portions immediately adjacent the work bed the upper forked portion would be cut longer than the lower one. After the binding has been fed through the 20 machine in the manner just described the guide 27 is reversed and its ends secured in the posts 29. The binding is then reversed and again fed through the machine as shown in Fig. 3 to remove the flash from the closed 25 side thereof. In this position of the binding it will be noted that the guides 24 and 27 and the presser foot 33 all coact to maintain the closed side of the binding in proper position for trimming.

30 The machine is simple and easily adjusted, and by merely reversing the position of the guide 27 it can be used to trim either the closed or forked sides of the binding.

Having thus described my invention what 35 I claim and desire to protect by Letters Patent is:

1. In a machine for trimming the flashed edges of a forked rubber binding, an edge trimming means, and guide means disposed wholly at one side thereof and coacting with the binding in advance and in rear of the trimming means to properly position for trimming the edges of either the closed or open side thereof.
2. In a machine for trimming the flashed edges of a forked rubber binding, an edge trimming means, and means including fixed and movable guides at one side of the trimming means for properly positioning the 45 edges of either side of the binding with respect to the trimming means.
3. In a machine for trimming flashed edges on binding, a cutter for trimming either side thereof, and guide means for positioning either side for trimming, said guide means including a reversibly mounted guide.
4. In a machine for trimming the edges of binding, cutting means disposed to trim 50 the binding at one side thereof, guide means for the other side of the binding, and removably mounted means for guiding and holding the binding against said guide means.
5. In a machine for trimming the edges 55 of binding, a grooved guide for one side

edge of the binding, removably mounted means for maintaining said edge against said guide, and offset rotary edge trimming means disposed to cut the opposite side of the binding.

6. In a machine for trimming the edges of forked binding, a guide for one side edge of the binding, removably mounted means disposed interiorly of the binding for maintaining said edge against the guide, and rotary cutting means spaced from the guide and disposed to cut the other side of the binding.

7. In a machine for trimming the edges of forked binding, a cutter, a guide laterally spaced therefrom, a coacting guide adapted to be disposed internally of the binding, and means whereby the last guide may be positioned adjacent either the cutter or the first guide.

8. In a machine for trimming the edges of forked binding, a cutter, a guide laterally spaced therefrom, a coacting guide adapted to be disposed internally of the binding, means whereby the last guide may be positioned adjacent either the cutter or the first guide, and an additional guide secured adjacent the cutter.

9. In a machine for trimming the flashed edges of a forked rubber binding, a rotary edge trimmer, a guide laterally spaced therefrom and adapted to coact with the binding, and guide means disposed internally of the binding.

10. In a machine for trimming the flashed edges of a forked rubber binding, a trimming mechanism, movable means for internally supporting the binding with either its closed or open side positioned for trimming; and exterior guides coacting with said means in either position of the binding.

11. In a machine for trimming the flashed edges of a forked rubber binding, a rotary edge trimming means, a fixed guide and support coacting therewith, and means including a plurality of other guides for properly positioning either edge of the binding with respect to the trimming means and fixed guide.

12. In a machine for trimming the flashed edges of a forked rubber binding, an edge trimming means, and coacting guides acting upon the exterior and interior of the binding for properly positioning the edges of either side of the binding for trimming.

13. In a machine for trimming the flashed edges of a forked rubber binding, the combination of means whereby both forked portions may be simultaneously trimmed at equal distances from the closed side of the binding, and means co-acting with the closed side for preventing lateral displacement of the binding during the trimming.

14. In a machine for trimming the flashed edges of a forked binding, a cutter, exterior

guides for the opposite edges of the binding, and interior guiding means adapted to coact with either of said exterior guides.

15. In a machine for trimming the flashed edges of a forked binding, means for exteriorly guiding the open and closed side edges of the binding, guide means disposed interiorly of the binding and adapted to coact with said first mentioned means, and a cutter disposed in operative relation to said first means.

16. In a machine for trimming the flashed edges of a forked binding, a cutter, and means coacting with the closed side edge of the binding for preventing lateral displacement of the binding during the trimming of either side.

17. In a machine for trimming flashed edges on binding, a cutter for trimming either side thereof, spaced guides each adapted to coact with either side of the binding, and a reversible guide adapted to engage the binding at the same part thereof irrespective of which side is presented to the cutter for trimming.

18. In a machine for trimming the flashed edges of a forked rubber binding, a work bed, a cutter disposed to operate above the surface of the bed, and means for spacing either the closed edge or the edges of the open side of the binding above the bed in operative relation to the cutter.

19. In a machine for trimming the flashed edges of a forked rubber binding, a guide for one edge of the binding, an adjustably mounted guide for the other edge, a cutter mounted adjacent one of said guides, and guide means disposed internally of the binding and movable to coact with either of the first mentioned guides.

20. In a machine for trimming the flashed edges of a forked rubber binding, a cutter, a fixed guide mounted adjacent the cutter, an adjustably mounted guide spaced from the first guide, and means disposed interiorly of the binding and movable to coact

with either of said guides to maintain either edge of the binding in trimming relation to the cutter.

21. In a machine for trimming the flashed edges of a forked rubber binding, a guide for one edge of the binding, an adjustably mounted guide for the other edge, a cutter mounted adjacent one of said guides, guide means disposed internally of the binding and movable to coact with either of the first mentioned guides, and a presser foot coacting with said first guide.

22. In a machine for trimming the flashed edges of a forked rubber binding, a work bed, a cutter, a lower binding guide coacting with the cutter, means for pressing the binding to the guide, a guide spaced from said first guide, interior guiding means for the binding, and means for supporting said last means in operative relation to either of said guides.

23. In a machine for trimming the flashed edges of a forked rubber binding, a work bed, a cutter, a lower fixed binding guide coacting with the cutter, means opposed to said guide for holding the binding thereagainst, a second guide spaced from said first guide and adjustable relatively thereto, interior guiding means for the binding, and means for supporting said last named guiding means in coöperation with either of said first guides.

24. In a machine for trimming flashed edges on binding, a rotary cutter, a transversely convexed guide extending longitudinally of the cutting edge and adjacent thereto, a presser foot coacting with said guide, a circular guide spaced from said first guide and having a grooved guiding periphery, means for adjusting said last guide to and from the first one, an intermediate guide, and means for supporting said last guide in different positions.

Signed at New York, N. Y., this first day of March, 1920.

WILLIAM J. KENT.
